UNITED STATES PATENT OFFICE.

RIVEN TOVE, OF SOUTH NORWALK, CONNECTICUT.

CORSET CLASP STAY.

Application filed October 14, 1922. Serial No. 594,503.

To all whom it may concern:

Be it known that I, RIVEN TOVE, a citizen of United States, residing at South Norwalk, county of Fairfield, State of Connecticut, have invented an Improvement in Corset Clasp Stays, of which the following is a specification.

This invention relates to corsets and particularly the clasp stays thereof.

10 It is an object of the invention to provide a clasp stay which will be more flexible than similar elements now generally used and one which will yield transversely in all directions as the wearer bends, but will return to its original position immediately the wearer straightens.

15 It is also an object of the invention to provide a clasp stay which will conform to all the curves of the body as the body of the wearer moves and will at all times hold the garment snugly thereagainst, and will provide such support as is necessary.

20 It is a further object of the invention to provide a clasp stay in which the probability of injuring the wearer is very remote, and also one in which the ends will not tend to force through the cloth of the corset, tearing the same and also injuring the wearer.

25 It is a still further object of the invention to provide a clasp stay which is not liable to breakage and so will reduce liability of injury to the wearer.

30 With these and other objects in view I have devised the construction illustrated in the accompanying drawing, in which—

35 Fig. 1 is a plan view of a portion of a corset showing my improved clasp stay applied thereto.

40 Fig. 2 is a detailed plan view of a portion of a stay.

45 Fig. 3 is a similar view of a stay having the other member of the corset securing means.

Fig. 4 is a transverse section substantially 50 on line 4—4 of Fig. 1.

Fig. 5 is a transverse section substantially 55 on line 5—5 of Fig. 1.

Fig. 6 is a section showing a different 60 method of constructing the stay.

50 Fig. 7 is a similar view of the stay carrying a securing element adapted to cooperate with that of Fig. 6.

Fig. 8 is a transverse section substantially 65 on line 8—8 of Fig. 6.

55 Fig. 9 is a transverse section substantially 70 on line 9—9 of Fig. 7.

Fig. 10 is a perspective view of a strengthening element which may be used with the construction illustrated in Figs. 6 to 9.

Fig. 11 is a view similar to Fig. 1 showing 60 a different construction of stay.

Fig. 12 is a section substantially on line 12—12 of Fig. 11.

Fig. 13 is a section substantially on line 13—13 of Fig. 11.

Fig. 14 is a view similar to Fig. 1, showing 65 a slightly different construction of stay, and

Figs. 15 and 16 are views similar to Figs. 2 and 3 respectively showing a different 70 form of securing means.

The body of the corset represented by the numeral 14 may be of any desired material in which is sewed in the usual manner stiffening elements such as 15 and the clasp 75 stays 16. In the form shown in Figs. 1 to 5 the stays are made with a plurality of supports 17 and 18 preferably of a short strip of flat metal carried by which, are the coacting securing elements, 19 and 20, the element 19 being in one piece with the flat metal element 17. These securing elements, when the stay is made up, are spaced from each other, and are connected by the flexible elements 21. These elements comprise flattened helical springs wrapped at their opposite ends tightly around the ends of the supporting elements 17 and 18.

80 The elements 17 and 18 may be of uniform widths throughout, but they are preferably reduced in width or narrowed at their opposite ends, as shown at 22 and 23, which narrow portions are embraced by the connecting spring elements. This provides 85 stop shoulders to limit the amount which the supporting elements may be inserted in the spring elements and also provides a stay of uniform width throughout. The adjacent turns of these spring elements are preferably in contact or substantially in 90 contact so that the body of the stay will not yield any appreciable amount longitudinally thereof, but will yield laterally in all directions. At the ends of the stays I 95

preferably use springs with the turns separated, as shown at 24, so that these tips will yield both longitudinally and laterally. This construction is disclosed in my co-pending application, Serial #564,747, filed 100 May 31, 1922.

110 In the construction illustrated in Figs. 6 to 10, the securing means, such as the

eye 25 and hook 26 are formed when the coils 27 and 28 are wound, by periodically extending out the loop thereof to provide the hook or the eye as the case may be, the stay being formed of a continuous helical coil.

In this type of construction the strain of the securing elements on the stay is localized on the two turns connected with the securing elements, and for that reason I prefer to place in the coil, at this point, a stiffening element 29 to distribute the strains of the securing means to adjacent coils.

In the form of construction shown in Figs. 11 to 13 I show how the principle of my invention may be applied where the securing elements such as hooks and eyes 30 and 31 respectively are secured to a tape 32, which tape is stitched to the free edges 20 of the corset to attach these hooks and eyes thereto. I attach this tape in the same manner by two spaced rows of stitches 33, 34 which provide a loop 35 through which may be inserted the stiffening element 36 comprising a continuous flattened helical spring with adjacent turns thereof in contact or substantially in contact. It will be apparent with this construction that I secure clasp stays which will yield laterally in all directions the same as those in the construction shown in Figs. 1 to 9, and will give substantially the same effect.

When the corset including my improved stays is worn the helical coil springs will hold the corset to the figure of the wearer without wrinkling the material and thus will secure the effect desired, as when the wearer bends or sits down instead of all this bend being compensated for at practically a single point in the body of the stay where there is the greatest leverage, as in flat metal stays, my stay will yield laterally throughout the length thereof as is required and remain tightly against the body 40 throughout the entire length of the stay. There will be no discomfort to the wearer as the pressure is uniform throughout. Immediately the wearer straightens the spring wires will come back to normal position 45 retaining the proper outlines to the figure and giving the proper yielding support.

As the stays are of flexible resilient material with no sharp ends or edges there is little probability of their breaking or injuring the wearer. With the ordinary flat steels, when they break, which is more or less common the sharp rough broken ends tear through the cloth of the corset and often cause serious injury to the wearer. 55 This danger is practically eliminated with my form of stay. The stay is very sensitive and so gives perfect freedom of movement.

It is sometimes desirable to have the lower half of the clasp stays stiffer than the up-

per half to provide a more rigid support at the lower half. I accomplish this by the construction shown in Fig. 14 in which instead of having the whole length of stay composed of flat elements 17 or 18 connected by springs or flexible elements 21, I use this construction only at the upper part of the stays and make the lower half of the stay of a single piece of flat sheet metal, as shown at 37 and 38. In effect the spring 75 connections 21 at the lower half of these stays are omitted and the elements 17 and 18 carrying the securing elements 19' and 20 are formed in one continuous piece.

In Figs. 15 and 16 I have shown a slightly different construction for the supports 17 and 18 and securing elements 19 and 20. In this construction I form one of the elements 39 with an eye 40 integral therewith and form the corresponding element 41 with 85 a hook 42 adapted to engage with the eye 40. The opposite ends of these elements are reduced at 43 and 44 respectively to correspond with reduced ends 22 and 23 of the elements 17 and 18 for insertion in the 90 ends of the flexible connecting elements 21.

Having thus set forth the nature of my invention, what I claim is:

1. A clasp stay for corsets including spaced securing elements, and flat coils of wire connecting said elements and arranged with their axes extending longitudinally of the stay, said coils being substantially non-compressible longitudinally of the stay but yieldable laterally in all directions. 95

2. A clasp stay for corsets including spaced securing elements and flat coils of wire between said elements, said coils being helical with the adjacent turns substantially in contact and arranged with their axes extending longitudinally of the stay. 105

3. A clasp stay comprising a plurality of flat spaced supporting elements, securing means attached to said elements, and flattened helical springs connecting said elements arranged with their axes extending longitudinally of the stay, the ends of the springs tightly embracing the ends of the supporting elements. 110

4. A clasp stay comprising a plurality of spaced flat supporting elements narrowed adjacent their ends to provide stop shoulders, securing means connected to said elements, and flattened helical springs connecting said elements and wrapped around the narrowed ends thereof, said springs being arranged with their axes extending longitudinally of the stay. 115

5. A clasp stay for corsets including spaced securing elements, flat coils of wire connecting said elements and arranged with their axes extending longitudinally of the stay, said coils being substantially non-compressible longitudinally of the stay but yieldable laterally in all directions, and sim- 125

ilar flat coils extending from the end elements, said latter coils being compressible longitudinally of the stay as well as laterally.

5 6. A clasp stay comprising a plurality of spaced supporting elements, securing means carried by said elements, flat helical springs connecting said elements and arranged with their axes extending longitudinally of the stay, the adjacent turns of said springs be-

ing substantially in contact, and flat helical springs extending beyond the end elements, the adjacent turns of the latter springs being spaced from each other to allow these springs to yield both longitudinally and laterally of the stay. 15

In testimony whereof I affix my signature.

RIVEN TOVE.
